ABSTRACT

A removable athletic shoe cleat wherein a generally frustoconical body portion, between a base and tip, provides a combination of angular gripping corners at and adjacent the tip and a plurality of upstanding gripping members adjacent the base.

ATHLETIC SHOE CLEAT

BACKGROUND OF THE INVENTION

This invention relates to a cleat for an athletic shoe, and more particularly to a removable cleat for a football shoe, which cleat provides improved traction on dirt, grass, and artificial playing surfaces.

SUMMARY OF THE INVENTION

It is an object of this invention to provide an athletic shoe cleat with improved traction.

This object can be achieved in a cleat providing a body portion intermediate the tip and base having a plurality of longitudinal grooves extending into the tip. The grooves and body portion intersect to form angular gripping corners on the body portion and tip. In addition thereto, can be provided a plurality of upstanding longitudinal gripping members on the body portion adjacent the base, which gripping members and gripping corners in combination improve the gripping power of the cleat.

BRIEF DESCRIPTION OF THE DRAWINGS

FIG. 1 is an elevational view of the cleat of this invention.

FIG. 2 is a horizontal view of the cleat of this invention.

FIG. 3 is an expanded view of the circled portion of FIG. 2.

FIG. 4 is an elevational cross sectional view taken along lines 4—4 of FIG. 2.

FIG. 5 is an elevational view with parts removed, of the cleat of this invention engaging a wrench used to replace the cleat.

DESCRIPTION OF THE PREFERRED EMBODIMENTS

Referring more particularly to the drawings, the best mode contemplated for carrying out the object of this invention is illustrated.

FIG. 1 shows a cleat 1 having a base 3 and a generally horizontal tip 5, with an intermediate body portion 7. The body portion 7 forms a generally frustoconical surface which converges downwardly from base 3 to tip 5.

The body portion 7 and tip 5 intersect to form angular edge 9, although edge 9 could be somewhat rounded.

A plurality of longitudinal grooves 11 are shown spaced at equal intervals in body 7 adjacent tip 5. The grooves 7 extend into or through the tip 5, as shown in FIG. 2, forming opening 13 therein, when viewed horizontally. The grooves 11 begin at about the middle of body 7 and deepen as they extend toward tip 5.

Edge 9 when viewed horizontally, as in FIG. 2, forms a generally circular shape lying on the surface of body 7. The circular-shaped edge 9 is divided into a plurality of arcuate segments 15 spaced apart by grooves 11 which extend radially on tip 5. Grooves 11 need not extend radially, however.

Referring to FIG. 3, sides 17 and 17' of groove 11 intersect with body 7 to form angular gripping corners 19 and 19' on body 7 for improved traction. Sides 17 and 17' also intersect edge 9 to form angular gripping corners 21 on tip 5 for improved traction.

Adjacent base 3 on body 7 is a plurality of upstanding longitudinal gripping members 23 spaced at equal intervals. Gripping members 23 begin on body 7 interme-

diate base 3 and tip 5 and gradually increase in height as they approach base 5. Gripping members 23 provide gripping means for engagement with a suitable wrench 25 for loosening and tightening as shown in FIG. 5. Upstanding gripping members 23 also provide improved traction, and in combination with gripping corners 19, 19', and 21 result in a cleat which provides improved gripping power, as well as a cleat which permits easy pivoting and turns of direction by the wearer.

Each upstanding member 23 is shown aligned with a corresponding groove 11 but they could be nonaligned without loss of effectiveness.

I prefer to space 16 grooves 11 and 16 gripping members 23 around body 7, although other numbers would do as well.

The cleat may be attached to a shoe in any suitable manner. As shown in FIG. 4, I prefer a centrally located recess 27 in base 3 which is presented toward the sole of the shoe. Internally threaded metal insert 29, preferably a square nut, is positioned within body 7 for receiving an externally threaded shoe stud (not shown) which is fastened to the shoe, as is well known. The bore 31 of insert 29 is axially aligned with the axis of body 7 and recess 27.

At the bottom of recess 27 shoulder portion 33 tapers to cover most of the outward surface of insert 29, leaving a small circumferential area 35 exposed to permit cleat 1 to contact the shoe stud without any interference.

Adjacent the inward side of insert 29 is a tapered stud-receiving aperture 37 axially aligned with bore 31 and recess 27. The surface 39 which defines aperture 37 extends into bore 31 to cover the last thread 41. Therefore, the horizontal dimension 43 of aperture 37 adjacent insert 29 is smaller than that of bore 31, insuring that the tip of the shoe stud will extend into surface 39 when the cleat is screwed on, locking the cleat to the stud.

In FIG. 5 is shown wrench 45 suitable for replacing the cleats of this invention. A head 47 forms internal surface 49 in which is located cavity 51 for receiving cleat 1. A plurality of grooves 53 are spaced around internal surface 49. Each groove 53 corresponds to and engages a mating upstanding gripping member 23 to provide the gripping means for turning the cleat 1.

Wrench 45 has shank 55 and handle 57 formed unitary with reenforcement ribs 59.

I prefer to make the cleat 1 from a rigid injection molded polyurethane but other materials such as hard rubber or nylon will do.

Cleat 1 can also be made integral with a shoe sole rather than removable.

I claim:

1. A cleat for a football shoe or the like comprising:
  - a. a base;
  - b. a tip;
  - c. a frustoconical body portion converging downwardly from said base to said tip, said body portion and said tip intersecting to form an edge;
  - d. a plurality of longitudinal grooves in said body portion, said grooves extending into said tip;
  - e. the intersection of the sides of said grooves with said body portion and said edge forming angular gripping corners on said body portion and said tip; and
  - f. a plurality of upstanding longitudinal gripping members on said body adjacent said base portion.

2. The invention of claim 1 in which said grooves are spaced on said body portion in equal intervals.
3. The invention of claim 2 in which said gripping members are spaced on said body portion in equal intervals.
4. The invention of claim 3 in which each of said grooves is aligned with a corresponding gripping member.
5. The invention of claim 1 in which said edge, when viewed horizontally, forms a generally circular shape 10 having arcuate segments spaced apart by said grooves.
6. The invention of claim 5 in which said grooves, when viewed horizontally, extend radially of said circular tip.
7. A cleat for a football shoe or the like comprising: 15
 a. a base;
 b. a tip;
 c. a body portion intermediate said tip and said base, said body portion and said tip intersecting to form an edge;
 d. a plurality of longitudinal grooves in said body portion, said grooves extending into said tip, each of said grooves beginning on the surface of said body portion and deepening as it extends into said tip;
 and

20
25

- e. the intersection of the sides of said grooves with said body portion and said edge forming angular gripping corners on said body portion and said tip.
8. A cleat for a football shoe or the like comprising:
- a base;
  - a tip;
  - a body portion intermediate said tip and said base, said body portion and said tip intersecting to form an edge, said body portion for attachment to said shoe including:
    - an internal recess in said base;
    - an internally threaded metal insert within said body portion adjacent said recess having a bore axially aligned with said body portion; and
    - an aperture adjacent the inward side of said metal insert axially aligned with said bore, said aperture having a smaller horizontal dimension than said bore;
  - a plurality of longitudinal grooves in said body portion, said grooves extending into said tip; and
  - the intersection of the sides of said grooves with said body portion and said edge forming angular gripping corners on said body portion and said tip.
